UNITED STATES PATENT OFFICE.

EDWARD B. ALLEN AND WILLIAM BARTLY SALMON, OF FLEMINGTON, NEW JERSEY, ASSIGNORS TO THE ALLEN AND VAN NEST COMPANY, OF FLEMINGTON, NEW JERSEY, AND NEW YORK, N. Y.

AUTOMATIC REGULATING DEVICE FOR STEAM-HEATERS.

SPECIFICATION forming part of Letters Patent No. 696,789, dated April 1, 1902.

Application filed February 11, 1901. Serial No. 46,889. (No model.)

To all whom it may concern:

Be it known that we, EDWARD B. ALLEN and WILLIAM BARTLY SALMON, citizens of the United States, residing at Flemington, in the county of Hunterdon and State of New Jersey, have invented certain new and useful Improvements in Automatic Regulating Devices for Steam-Heaters; and we do hereby declare the following to be a full, clear, and exact description of the invention, such as will enable others skilled in the art to which it appertains to make and use the same.

Our invention is an improvement in automatic regulating devices for steam heating apparatus; and it consists in the novel features hereinafter described, reference being had to the accompanying drawings, which illustrate one form in which we have contemplated embodying our invention, and said invention is fully disclosed in the following description and claims.

Referring to the said drawings, Figure 1 represents a side view of a steam-heater, showing our improved regulating apparatus applied thereto. Fig. 2 is a similar view showing the parts in different positions. Fig. 3 is a top plan view of the heater and regulating apparatus. Figs. 4, 5, and 6 are side views of the upper part of the heater, showing our apparatus in different positions. Fig. 7 is a partial rear view of the heater.

The object of our invention is to provide a cheap and simple apparatus which will give a wide range of control of the heater and which will be operated by the steam-pressure generated in the heater. To this end our apparatus is arranged to control the draft damper or door, the smoke-pipe damper, and the check-draft and is so constructed and arranged that it will first close the draft-door without altering the positions of the other parts, then will close the flue or smoke-pipe damper, and then on further movement will open the check-draft. With this wide range of control the heater will control itself, and by means of an adjustable weight the apparatus can be left entirely without care for long periods and will automatically control the fire, so as to maintain a predetermined steam-pressure.

In the drawings, A represents a steam-heater, which may be of any usual or preferred form, in which a represents the lower draft-damper, consisting in this instance of a door hinged along its upper edge. a' represents the usual flue or smoke-pipe damper provided with a reduced central aperture. a² and a³ represent a check-draft door normally closing an aperture in the smoke-pipe in rear of the flue-damper for admitting air directly into the flue, and thus depriving the fire of even the small draft afforded by the reduced aperture a² in the flue-damper a'.

The pivotal shaft a⁷ of the flue-damper a' is provided with an operating-arm a⁴, herein-after referred to, and a shorter arm a⁵, which is adapted to engage an arm or bracket a⁶, connected with the check-draft door a³ when the flue-damper has been moved into position to substantially close the smoke-pipe A', so that when the damper a' has been closed any further movement of the arm a⁴ will cause the arm a⁵ to engage the arm a⁶ and raise and open the check-draft door a³.

A² represents a steam-outlet pipe or main connected with the steam-generating chamber of the heater, and A³ represents a steam-pipe also connected with the generating-chamber and provided with a diaphragm-governor A⁴, having a piston or actuating-rod A⁵. The construction of these diaphragm-governors is so well known as to need no particular description, it being understood that the pressure of steam in the generating-chamber causes an upward pressure on the diaphragm, and thus raises the rod or piston A⁵.

We preferably provide a collar to clamp around the main A² and carry the levers forming part of my apparatus. This collar consists of two parts B B, formed to fit around the pipe A² and connected by bolts and nuts. One of the parts B is provided with a projection or stud b, on which is pivotally mounted a lever C, having one end extending forward, so as to clear the front of the heater, and its other end provided with a counterbalance-weight D, adapted to be moved along the lever to vary the pressure of steam required to operate the device.

The governor A⁴ is provided with a lifting-

- lever A^6 , pivoted at one side of the same, engaging the upper end of the piston or rod A^5 and having its free end extending beneath and in contact with the rear end of lever C.
- 5 The front end of lever C is connected by a chain or other flexible connection E with the draft-door a , said chain being so arranged that when there is no pressure of steam in the generating-chamber the weight D will hold 10 the draft-door a open, as shown in Fig. 1.
- F represents a second lever, pivoted between its ends to one of the parts B of the clamping-collar, as shown, and having its rear end connected by a chain f or other flexible connection with the arm a^4 of the flue-damper, the said chain being so arranged that when the damper a' is open (in which position it will be normally held by the weight of the arm a^4) the said chain will be slack.
- 15 20 until after the damper a has been closed by the movement of lever C. The forward end of lever F is pivotally connected to the forward end of lever C by a pin (or bolt) f^2 and slot connection, permitting a small amount of play to prevent binding the parts, and lever F is preferably provided with a series of apertures f' , in which the pin or bolt f^2 may be inserted, so as to change the leverage thereof to secure the desired movement of the rear 25 30 end of the lever and to regulate the extent to which the check-draft may be opened. The lever C is provided with a slot c to engage the pin or bolt f^2 .

The operation of the parts will be as follows:

- 35 Supposing the parts to be in the position indicated in Figs. 1 and 4, the draft-damper a being open, the flue-damper a' fully opened, and the check-draft closed, a fire is started in the heating apparatus, and the weight D 40 is moved to the desired position on the lever C to maintain a given steam-pressure in the heater. As soon as this degree of pressure has been reached in the heater the diaphragm-governor A^4 will cause its rod A^5 to rise, there- 45 by partially elevating the lever A^6 and raising the rear end of lever C. This will cause the depression of the forward end of lever C and will first close the draft-door a and at the same time move the lever F so as to take up 50 the slack of chain f , connected with the flue-damper. This position of the parts is indicated in Fig. 5. If the closing of draft-door a does not sufficiently check the fire and the pressure rises in the heater, the further upward movement of the rear end of lever C will cause lever F to lift arm a^4 and partially or wholly close the flue-damper a' and bring arm a^5 in position to engage arm a^6 , as 55 shown in Fig. 6. Should the pressure yet in- 60 crease, the further upward movement of lever C will cause lever F to raise arm a^4 still

farther, and the arm a^5 will lift arm a^6 , and thereby open the check-draft door a^3 , as shown in Fig. 2. As the pressure falls the check-draft will first be closed, then the flue-damper will be opened, and lastly the draft-door will be opened. By this means there are three separate devices for controlling the fire, all independently under the control of the diaphragm-governor and arranged to be 65 operated in a predetermined order under all circumstances, thus insuring a very regular and even pressure and temperature.

What we claim, and desire to secure by Letters Patent, is—

75

1. The combination with a steam-generator provided with a draft-damper, a flue-damper and a check-draft, of regulating devices including a clamping-collar adapted to be secured to a pipe connected with the generator 80 and provided with two oppositely-extending arms, an operating-lever pivoted to one of said arms, a connection providing for lost motion extending from one end of said lever to the draft-damper, a governor actuated by 85 steam-pressure operatively connected with said lever, a second lever pivoted to the other arm of said collar having one end movably connected to said first lever and the other end connected to the flue-damper, said con- 90 nections providing for lost motion and connections also providing for lost motion between said second lever and the check-draft, substantially as described.

2. The combination with a steam-generator 95 provided with a draft-damper, a pivoted flue-damper and a check-draft damper in the smoke-pipe adjacent to the flue-damper, of regulating devices including an operating-lever, a steam-pressure governor connected therewith, a connection providing for lost motion between said lever and the draft-damper, a second pivoted lever having one end operatively connected with the first lever, an operating-arm on the pivot of the flue-damper, 100 a connection providing for lost motion extending from said arm to the free end of said second lever, a second arm on the pivot of the flue-damper and a part connected with the check-draft damper normally out of engagement with said second arm but adapted to be engaged thereby when the flue-damper is closed, to open the check-draft damper, 105 substantially as described.

In testimony whereof we affix our signatures in the presence of two witnesses.

EDWARD B. ALLEN.

WILLIAM BARTLY SALMON.
